UNITED STATES PATENT OFFICE.

CARL BORNMANN, OF BINGHAMTON, NEW YORK.

RECORDING DEVICE FOR AUTOMOBILES.

1,218,364.

Specification of Letters Patent. Patented Mar. 6, 1917.

Application filed November 2, 1916. Serial No. 129,071.

To all whom it may concern:

Be it known that I, CARL BORNMANN, a citizen of the United States, and a resident of the city of Binghamton, county of Broome, and State of New York, have invented a new and useful Recording Device for Automobiles, of which the following is a specification.

Those who are accustomed to run automobiles frequently find necessity for some means of making a record of the occurrences that transpire while on the road. Indeed sometimes a record made at the time is not only a convenience but is practically essential for the protection or subsequent use of the chauffeur or owner. As, for example, in the event of an accident, an arrest, a misdirection, distance traveled, or similar occurrences, and when occasion arises to make such record usually there is no suitable material upon which to make it, so that resort must be had to some scrap of paper or other inconvenient or undesirable material which may be accessible. It is the purpose of this invention, therefore, to provide a convenient, always present, compact and instantly available means upon which the record can be made and which is so constructed that ready reference may be had to previously made records, and also so that the record may be removed from the device and folded or rolled for permanent preservation.

Referring to the drawings, Figure 1 is a perspective view illustrating the invention mounted upon the front board of an automobile; Fig. 2 is an edgewise elevation of a device embodying the invention, partially in section; Fig. 3 is an elevation of the rear of the device shown in Fig. 2, disclosing its interior construction, portions being broken away; Fig. 4 is a vertical sectional view on the line 4—4 of Fig. 3, looking in the direction of the arrows.

In the drawings 1 represents the foot board of an automobile, 2 the front board, 3 a device embodying my invention supported upon the front board 2. The body of the device is preferably made in the form of a rectangular metallic frame 4, open front and back, and having preferably flanges 5, 5, in the front, leaving an open space between them, within which is supported a writing tablet or board 6, having smooth curved ends 7, 7. The tablet may be a separate piece of metal or integral with the side pieces of the frame. 8 is a door hinged at its lower edge

9 to the body of the frame, so that it is adapted to be swung open as shown in dotted lines in Fig. 4. At each side of the door there is a flange 10 (seen best in Fig. 2) with an extended lower portion through which a rivet or equivalent device 11 passes to form the pivotal joint 9, there being of course one such on each side of the frame. At its upper end the material forming the door is rolled over as at 12, thus forming a latch-like structure which engages with the top of the frame and holds the door locked when closed, and at the bottom there is another rolled over part 13, which, when the door is fully open, rests against the underside of the bottom of the frame and supports the door, so that when in that position it may act as a hand rest for the person making the record.

14 and 15 are two spindles, each mounted upon an axis 16. Upon one end of each spindle there is a thumbnut 17, whereby each spindle may be turned in either direction. I prefer that these spindles should be provided with flanges 18, thus making them in effect spools.

19 is a shaft which extends across the frame from one side to the other midway between the spindles, upon which are mounted springs 20, preferably in such manner that they may rock or oscillate upon the shaft, and from each spring there are two projecting terminals 21, which engage loosely in clips 22 formed upon or cut out from curved compression plates 23, which press upon the paper, or equivalent material 24 wound upon the spools, exerting such pressure thereon as to secure smooth, even winding thereof and tension over the writing tablet 6. 25, 25, are two laterally projecting ears flush, or substantially so with the rear edge of the sides of the frame through each of which a key hole opening 26 is made, within which a headed bolt or screw 27, which is fastened in the front board 2 of the automobile, may be inserted, whereby the recording device may be quickly and easily attached to and detached from the front board. In order to avoid possibility of scratching or otherwise defacing the front board I prefer to line the faces of these ears with felt, or equivalent material 28.

29, 29, are two spring clips, which may beneficially be made in the form shown in Figs. 2 and 4. They may be separate pieces

riveted or otherwise attached to the frame or may be punched out of the frame material itself. They serve as means for rigidly holding a pencil 30.

5 In order that the spools may be readily inserted and removed from the frame for the purpose of removing a record once made and inserting fresh paper for further use, I prefer to make the journals of the spools 10 in the form of continuous slots 31 extending from the rear edge of the side of the frame inwardly toward the center and, as will be seen best in Figs. 2 and 4, I make the slot which is adjacent to the winding thumbnut 15 of each spool somewhat wider than the companion slot on the opposite side so that the hub of the winding nut may be received within the slot, thus affording a somewhat better bearing and freedom from jamming 20 or binding of any of the parts.

The operation is as follows: To apply the extended strip of record paper or equivalent material, an appropriate spool, preferably the lower one, is removed from the 25 frame and the paper is coiled upon it in a manner well understood. The spindles of the spools have slits made in them to receive the tapered end of the paper as usual in such structures. The compression plate 23, 30 which normally engages with the spool, is then lifted, compressing the springs 20 in so doing, and the spool is dropped into place, its axis passing through the slots 31 to the bottom thereof. The pressure plate is then 35 released which will take a bearing upon the exterior surface of the paper wound upon the spool. The end of the paper has previously been passed through the opening between the lower edge of the writing tablet 6 40 and the lower flange 5 of the frame. The exposed end of paper is then gently pulled upon until sufficient has been unwound to pass its end through the slit between the upper end of the writing tablet 6 and the 45 upper flange 5 of the frame and its end is then in like manner attached to the spindle 14 of the upper spool. Thereupon the upper spindle is turned by its thumbnut in a manner well understood until the paper has been 50 drawn snugly down upon the writing tablet and has made two or three convolutions about the upper spindle. Thereupon the 55 door being closed, the device is hung upon the front board of an automobile by suitably engaging the key hole openings in the ears 25, 25, with the bolts or screws 27 as above stated.

When it is desired to make a record the operator taking hold of the rounded upper 60 edge of the door pulls it forwardly and downwardly as far as desired. If it is moved so far that the lower rounded edge 13 comes in contact with the under side of the frame, it will be found that the cover affords 65 a convenient hand rest to aid in making the

record. The lowering of the cover will expose the record paper stretched across the outer surface of the writing tablet in a convenient manner for making the record thereon. The record, whatever it may be, and of 70 such length as may be desired, is then written upon the paper, the pencil for so doing being always conveniently at hand, supported upon the under side of the tablet by the pencil holding clips 29. The record 75 being made, the cover is again closed which protects it against rain, the spattering of mud or other defacement. In the record should be so long as to consume more of the paper than was in the first instance stretched 80 across the face of the writing tablet, then upon turning the thumbnut of the upper spool additional clean paper will be unwound from the lower spool and brought into position over the writing tablet. In 85 this way record after record may be made, indefinitely until all of the paper has been unwound from the lower spool to the upper spool and if at any time it shall become desirable so to do, the record may be wound 90 back by appropriate manipulation of the winding key of the lower spool so that the paper will be back wound from the upper spool to the lower spool until the desired record be reached, whereupon the paper may 95 be rewound upon the upper spool again. When all of the paper has been used up the entire device will be detached from the front board of the automobile by simply lifting it in such manner that the headed screws or 100 bolts 27 are disengaged from the key hole slots 26 in the ears 25, whereupon the structure being turned over and the spools taken out, the paper bearing the record may be 105 removed and fresh paper supplied. 110

It will be noted that inasmuch as the spring pressure devices are adapted to an oscillating or rocking movement upon the shaft 19, which supports them, that they automatically adjust themselves to the size 110 of the paper wound upon the respective spools; that is to say, as one spool decreases and the other increases in size the spring pressure or tension devices will automatically rock upon their supporting shaft, thus 115 maintaining uniform pressure upon the two spools.

It will be obvious to those who are familiar with such matters that the embodiment of my invention above described and illustrated is one form only in which the essentials thereof may be employed. I therefore do not limit myself to the details of construction. 120

I claim: 125

1. A registering device comprising an exterior frame all the sides whereof are closed and having an open back and front, two spools journaled in slots made in opposite sides of the frame, means to rotate the 130

spools in either direction, a writing tablet somewhat smaller than the opening in the front of the frame, a drop cover hinged to the lower part of the frame and which entirely closes its front, protecting the record, and a spring pressure friction device engaging each spool.

2. A registering device comprising an exterior frame all the sides whereof are closed 10 and having an open back and front, two spools journaled in slots made in opposite sides of the frame, means to rotate the spools in either direction, a writing tablet somewhat smaller than the opening in the frame, 15 a drop cover hinged to the lower part of the frame and which entirely closes its front, protecting the record, a spring pressure friction device engaging with each spool, and compression plates on the free ends of 20 the springs.

3. A registering device comprising an exterior frame having an open front and back, two spools journaled on opposite sides of the frame, means to rotate the spools in either 25 direction, a writing tablet somewhat smaller than the opening in the front of the frame and having rounded ends, a cover to close the front of the frame and act as a protector of the record, and spring pressure devices 30 adapted to automatically rock on their sup-

port and thus equalize the tension on both spools as their diameters vary and compact the paper thereon.

4. A registering device comprising an exterior frame having an open front and back, 35 two spools adapted to be inserted within and removed from and supported by opposite sides of the frame, means to rotate the spools in either direction, a writing tablet the opposite sides whereof are smoothly rounded and which is somewhat smaller than the opening in the front of the frame, a single solid cover hinged at its lower edge to and which closes the front of the frame and protects the record, and spring pressure 40 devices adapted to automatically rock on their support and thus equalize the tension on both spools as their diameters vary and compact the paper thereon. 45

5. A registering device comprising an exterior frame, two spools journaled within the frame and suitably supported tension devices located between the spools and compression plates on the free ends of the tension devices which automatically oscillate 50 on their supports as the respective diameters of the spools vary. 55

In testimony whereof I have signed my name to this specification.

CARL BORNMANN.
